Primary Examiner — George D Kirschbaum

(57) **CLAIM**

The ornamental design for a lens for a motion detector in a decorative lighting fixture, as shown and described.

DESCRIPTION

FIG. 1 is an overall perspective view of a decorative lighting fixture including a motion detector with a lens showing our design;

FIG. 2 is a front elevational view of the motion detector lens of FIG. 1 with a portion of the lighting fixture shown in broken lines; and,

FIG. 3 is a right elevational view of the motion detector lens of FIG. 1 with a portion of the lighting fixture shown in broken lines; the left elevational view is a mirror image.

The top, rear and bottom of the motion detector lens in the lighting fixture contain no elements of the claimed design and are not visible in ordinary use.

The broken lines in the Figures are shown for illustrative purposes only and do not form part of the claimed design. A characteristic feature of the design resides in the bulging "barrel" shape of the lens.
